UNITED STATES PATENT OFFICE.

WALLACE H. BATE, OF MELROSE, MASSACHUSETTS.

WATER-SUPPLY APPARATUS FOR TANKS.

SPECIFICATION forming part of Letters Patent No. 351,732, dated November 2, 1886.

Application filed February 1, 1886. Serial No. 190,453. (No model.)

To all whom it may concern:

Be it known that I, WALLACE H. BATE, of Melrose, in the county of Middlesex and State of Massachusetts, have invented certain new and useful Improvements in Water-Supply Apparatus for Tanks, of which the following is a specification.

My invention relates to water-supply apparatus for tanks, and more particularly to tanks for water-closets, and has for its object to provide improved means whereby the water may be suddenly "shut off" when the tank becomes sufficiently full, and as suddenly "turned on" when the water is lowered in the tank.

15 My invention will first be described in connection with the drawings, and subsequently pointed out in the claims.

In the drawings hereto annexed, and forming a part of this specification, Figure 1 represents a longitudinal vertical section of a tank equipped with a supply apparatus embodying my invention, representing the water as turned on. Fig. 2 is a like view representing the water as shut off.

25 Similar letters indicate similar parts in both figures.

In the drawings, *a* represents the tank, and *b* the supply-nozzle, secured on the upper edge of the side of the tank, and to which a ball-cock, *c*, of a character and construction commonly employed in contrivances of this kind, is attached.

d represents a rod, attached at one end to ball-cock *c*, and at the other end to one end of a bell-crank lever, *e*, as shown. Toward the free end of arm *f* of lever *e* the float *g* is secured in the usual manner. A weight, *h*, provided with lugs *i*, between the upper ends of which is journaled a roller, *j*, is hung upon said arm *f* between the float and the elbow of the lever by passing the arm between the lugs and weight and roller, by which arrangement the roller is adapted to travel freely on said arm between the float and elbow of the lever, so that when the float is lower than the elbow of the lever the roller will carry the weight *h* down against the former, as represented in Fig. 1, and when the position of the parts is reversed, as shown in Fig. 2, the roller will 45 run down upon said arm *f* and carry the weight to the elbow-point of the lever.

k represents a bell-crank lever pivoted at its elbow to the outer end of arm *f*, and having its vertical arm *l* extending up through a slot, *m*, formed in a slot or projection, *n*, secured to the side of or extending across the tank. Said arm *l* has a notch, *o*, formed in its side near its upper end, by which means arm *f* of lever *e* and its attached float may be depressed, and locked in that position by engaging the notch *o* of arm *l* with the edge of the slot *n*, as represented in Fig. 1.

To the outer end of arm *p* of bell-crank lever *k* is rigidly secured a rod, *r*, provided near its upper end with a collar, *s*, rigidly though adjustably secured thereto. A float, *t*, is arranged on rod *r*, between the outer end of arm *p* of lever *k* and collar *s*, so as to slide loosely on said rod, but to be arrested in its upward movement thereon by collar *s*.

It will be seen that the levers, floats, rod, weight, &c., described are all hung to the outer end of rod *d*, which is secured to ball-cock *c*, and tend, when the water is out of the tank, to move said rod to the position represented in Fig. 1, and open the cock, in a manner that will be readily understood, allowing the water to run into the tank, and when the parts are all in this position the roller *j* and its attached weight will be in contact with float *g*, and the notch *o* of arm *l* will engage the slot *n* and lock the parts in the position described.

As the tank fills with water, float *t* will rise on rod *r* independent thereof until it comes in contact with collar *s*, when it will raise said rod with it, thus rocking elbow-lever *k* on its pivot, throwing back arm *l* thereof and unlatching it from slot *n*, allowing float *g* to rise until arm *f* reaches an inclination which will permit roller *j* and its attached weight *h* to run back to the elbow-point of lever *e*, by which means the outer end of a rod, *d*, will be suddenly depressed, closing cock *c* and stopping the flow of water in the tank. When the tank is emptied so as to permit the float *t* to come in contact with and not upon arm *p* of lever *k*, its weight, added to the weight of float *g*, will overbalance weight *h*, and incline arm *f* of lever *e* in the opposite direction, when roller *j* and its attached weight will run quickly down on arm *f* and suddenly reverse the

position of the parts and open the cock for the flow of water into the tank. By this latter movement the notch in arm *l* will automatically become engaged with slot *n*, locking the parts in their former position, as represented in Fig. 1.

By my invention I secure a full and continuous flow of water until the tank is filled, thus filling the tank in less time than where the valve is gradually closed and the water in like manner shut off, and by opening and closing the valve suddenly I avoid the wear on the packing of the valve which is occasioned by the water in gradually opening and closing the same.

It will be noticed that lever *k* and its adjuncts may be dispensed with, and the remainder of the contrivance operated with improved results, the weight under these circumstances holding the float down until the water in the tank is sufficient to lift it and float *g* to such a height as to incline arm *f* of elbow-lever *e* to such a degree that roller *j*, carrying weight *h*, will run down to the elbow-point of said lever, thus quickly depressing the outer end of rod *d*, closing the cock, and stopping the flow of water into the tank.

Having thus described my invention, I claim—

- 30 1. A water-tank supply apparatus consisting of a nozzle, a ball compression-cock connected therewith, a rod connected at one end to said cock, an elbow-lever having one of its arms connected to the other end of said rod, a float connected to the other arm of said lever, and a weight adapted to move to and fro on said last-mentioned arm as said float is raised and lowered by the water in the tank, as set forth.
- 35 2. A water-tank-supply apparatus consisting of a nozzle, a ball compression-cock connected therewith, a float, a rod, and an elbow-lever connecting said float with said cock, a weight adapted to move to and fro on one of

the arms of said lever as said float is raised and lowered in the tank, mechanism, substantially as described, for locking said float in its depressed position, and a supplemental float for operating upon said mechanism to automatically unlock or release said first-mentioned float from its depressed position as the tank fills with water, as set forth.

3. A water-tank-supply apparatus consisting of a nozzle, a ball compression-cock connected therewith, a float, a rod, and an elbow-lever connecting said float with said cock, a weight adapted to move to and fro on one of the arms of said lever as said float is raised and lowered in the tank, mechanism, substantially as described, for locking said float in its depressed position, and a supplemental float operating upon said mechanism as the water falls in the tank to automatically lock said first-mentioned float in its depressed position, and as the water rises and fills the tank to unlock or release it, as set forth.

4. The combination, with the cock *c*, float *g*, and rod and lever connecting said float with said cock, of the bell-crank lever *k*, connected to said first-mentioned lever and having one of its arms notched, as described, the slot *n*, rod *r*, secured to the end of the other arm of said lever, collar *s*, secured to said rod, and float *t*, as set forth.

5. The combination of the cock *c*, rod *d*, bell-crank lever *e*, weight *h*, adapted to move on one arm of said lever, float *g*, bell-crank lever *k*, notched as described, slot *n*, rod *r*, provided with the collar *s*, and float *t*, as set forth.

In testimony whereof I have signed my name to this specification, in the presence of two subscribing witnesses, this 28th day of January, 1886.

WALLACE H. BATE.
